APPARATUS FOR AGING AND PURIFYING LIQUORS

Benjamin A. Plume, Somerville, Mass.

Application October 8, 1934, Serial No. 747,264

8 Claims. (Cl. 99—277.2)

This invention relates to apparatus for aging and purifying liquors.

The invention has for an object to provide a novel and improved apparatus for aging and purifying liquors, particularly distilled alcoholic liquors, within the barrels in which such liquors are stored in the bonded warehouses, and with which such liquors may be aged and purified in a rapid, economical and practical manner.

10 A further and more specific object of the invention is to provide a novel and improved apparatus of the character specified, which is adapted to enable liquors to be purified and aged within the barrels in which the liquor is stored 15 in a storage warehouse under conditions which lend themselves to most efficient and accurate control of the process by which the liquors are being aged.

With these general objects in view, and such others as may hereinafter appear, the invention 20 consists in the apparatus for purifying liquors hereinafter described and particularly defined in the claims at the end of this specification.

In the drawing illustrating the preferred embodiment of the invention, Fig. 1 is a vertical sectional view illustrating the present apparatus installed in operative position in the barrel in which the liquor is stored in a bonded warehouse; and Fig. 2 is a detail in vertical section taken at 25 right angles to the section of Fig. 1 and illustrating the relationship between the heating coil and the stirrer member.

At the present time whiskey is stored in bonded warehouses in barrels under Government supervision, and in order to remove impurities, the usual practice has been to retain the barrels of whiskey in the storage warehouse for a number of years in order to permit the removal of the impurities by contact of the whiskey with the 30 inner surface of the barrel. The present apparatus is adapted to hasten the aging of liquor in the barrel in which it is stored in the bonded warehouse, and in practice, the liquor may be purified within a period of a few days to the same extent as has heretofore been possible by storage 35 over several years. The present apparatus is designed for use in purifying the liquor within the original barrels and without adding or detracting from the contents of the barrel, and accordingly 40 comprises, in general, a heated element and a stirring element mounted in and operatively supported by a bung member of a size adapted to fit into the usual bung hole in the standard barrel in which the liquor is stored within the bonded 45 warehouse. The apparatus is provided with a

motor for operating the stirring member, and with an expansion chamber into which the fumes and vapors from the liquor may rise during the purifying process. Provision is made for condensing such vapors and returning them to the barrel during the operation of the apparatus. In order to accurately determine the rate of heating and the temperature of the liquor within the interior of the barrel, the apparatus is provided with a thermometer, and provision is preferably made for circulating the liquor from within the interior of the barrel around the bulb of the thermometer and returning the same to the barrel, to the end that accurate temperature readings may be obtained. The stirring device is preferably shaped to sweep the interior walls of the barrel and is arranged with respect to the heating member, and both are made of such shape as to enable them to be readily inserted into the barrel through the usual bung hole therein when the apparatus is installed for operation.

Referring now to the drawing, 10 represents the standard barrel, which usually has a charred interior and within which it is the present practice to store liquor within the bonded warehouses 25 for purposes of aging and purifying the same under Government supervision and control. In accordance with the present invention, a unitary apparatus is provided comprising a stirrer member 12 and a heating member 14. As herein shown, the stirrer member 12 is of general hook shape and formed upon the lower end of a vertical operating shaft 16 journalled in a suitable lower bearing 18 in a block 20, the lower end of which is threaded and constitutes a bung 22 of 30 the exact size and adapted to fit into the standard bung hole of the barrel 10. The block 20 is bored for the reception of the free ends of the heating pipes 14 and for the reception of supply and exhaust pipes 24, 26 through which steam or 35 other heating medium is circulated from any convenient source of supply (not shown). The apparatus is further provided with an expansion or vapor chamber 30, preferably comprising two copper hemispheres bolted together and mounted 40 upon the block 20 to form a unit therewith. The chamber 30 is also arranged to operatively support a supporting member 32 constituting a bearing for the upper end of the shaft 16 and having a support 34 upon which an electric motor 36 is 45 removably secured. The motor 36 is connected to the shaft 16 through any suitable driving connections herein shown, as a worm 38 and worm wheel 40, whereby the rotations of the armature of the motor may be reduced and transmitted to 50

the shaft 16. A suitable stuffing gland 42 and packing 44 are provided for maintaining a vapor-tight joint at the upper bearing 45 for the shaft 16. The chamber 30 is provided with a vent pipe 46 mounted in and extended through the block 20 for permitting the vapors from the liquor within the barrel 10 to expand upwardly into the chamber 30 during the operation of the apparatus. The chamber is further provided with a cooling coil 50 through which a cooling medium such as cool water may be circulated through supply and exhaust pipes 52, 54, to efficiently condense the vapors in the chamber 30, and the condensate is returned by gravity through a drip or return pipe 48.

Provision is made for accurately determining the temperature of the liquor within the interior of the barrel during the entire aging process, and to this end, the apparatus is provided with a thermometer or other temperature recording instrument, herein shown, as comprising a thermometer 60 of standard make, having the base 61 of its casing formed at right angles to the main body of the thermometer, and threaded and screwed into a threaded hole in a casting 62 through which the stirrer shaft 16 is arranged to extend. The casting 62 is provided with a stuffing gland 64 for maintaining a vapor tight joint, and has secured to it a second casting 66 which forms with the casting 62, a housing for the reception of a gear pump 68 of any usual or preferred construction, and which may be purchased in the open market. The casting 66 is also provided with a stuffing gland 67 for maintaining a vapor tight joint between it and the rotary shaft 16. The gear pump 68 is arranged to be actuated by the rotation of the shaft 16, and one member 69 of the gear pump is secured to the shaft 16. Operating passages are provided through the stirrer member 12 and castings 66 and 62, respectively, to form an inlet passage, indicated generally at 71, leading from the interior of the barrel through the inlet opening 72 in the stirrer member to permit a stream of liquor to be conveyed upwardly through the passage 71 in the stirrer member by the action of the gear pump and to be forced through the portion of the passage 71 in the casting 62 into an elongated chamber 74 in the casting 62, and into which the bulb 76 of the thermometer is arranged to extend. From the chamber 74, the liquor is returned to the interior of the barrel through an outlet pipe 77 mounted in the block 20, and in this manner, during the operation of the apparatus, a continuous circulation of liquor is caused to take place from within the barrel, up through the stirrer member, around the bulb of the thermometer, and thence back to the barrel, so that the readings of the thermometer indicate accurately the operating temperature of the liquor being aged. In practice, it is preferred to maintain the liquor, during the aging process, at temperatures from 145° F. to 155° F.

In order to effect most efficient and most uniform heating of the liquor throughout the entire body of liquor within the barrel, and at the same time, to enable the heating element 14 to be readily inserted into and withdrawn from the barrel through the usual bung hole therein, it is preferred to shape the heating element 14 in the manner illustrated in Figs. 1 and 2, in which the heating element sweeps the sides of the barrel for a portion of its length and terminates in a hook shaped end portion, so that the entire heating element may be readily withdrawn from the

barrel through the bung hole. The stirrer member 12 is also shaped to conform closely to the curvature of the main body of the heating element, so that both the stirrer member and heating element may be readily withdrawn from the barrel and also introduced therein. The shapes of the stirrer member and of the heating element are such that the heating element does not interfere with the rotary movement of the stirrer member. Insulating gaskets 80, 81 are preferably provided to reduce to a minimum the transmission of heat from the circulating stream of liquor, by which the temperature readings are taken, to the end that the thermometer may indicate most accurately the true temperature of the liquor within the barrel.

In some instances, I may prefer to assist the normal agitation produced by the rotation of the stirrer member 12 in a general longitudinal direction, by the provision of a deflecting blade 84 on the end of the stirrer in order to reduce vertical agitation in the body of liquor within the barrel.

From the description thus far, it will be observed that the present apparatus comprises a unitary structure from which the motor 36 may be readily removed providing a remaining unit which may be constructed of relatively light weight, to be capable of being transported from barrel to barrel within the storage warehouse and of being handled in such manner as to enable the heating and stirring elements to be conveniently introduced into and withdrawn from the barrel. In the operation of the apparatus, the aging is effected by continual agitation of the liquor in a heated condition, and it will be observed that during operation, the liquor remains sealed from the atmosphere, preventing contamination and the introduction of extraneous material into the liquor. This feature of the invention is of importance in order to comply with government regulations. The provision of the condensing coils and return drain from the expansion chamber 30 insures the return to the barrel of all liquor vapor which may pass upwardly through the vent pipe into the chamber 30. The provision of the thermometer and the circulating system for effecting continual circulation of the liquor from the interior of the barrel around the bulb of the thermometer, enables the operating temperature of the liquor to be accurately determined and carefully controlled within the required limits, thus contributing to the success of the aging operation. By mounting the thermometer upon the casing forming the chamber 30, the occasion for perforation of the barrel is eliminated.

While the preferred embodiment of the invention has been herein illustrated and described, it will be understood that the invention may be embodied in other forms within the scope of the following claims.

Having thus described the invention, what is claimed is:

1. Apparatus for aging distilled alcoholic liquor in a storage barrel of the usual type provided with a conventional bung hole, said apparatus having, in combination, a curved heating element and a stirring element rotatable with respect to said heating element and capable of being simultaneously inserted into and withdrawn from said barrel with said heating element through said bung hole, supporting means for the stirrer element and heating element, said means being adapted to be secured in the bung hole to seal

the same, a closed chamber mounted upon the supporting member to form a unit therewith, a vent pipe leading from the interior of the barrel through the supporting member for conducting the vapors into said chamber, a condensing coil within the chamber, and a return drain from the chamber to within the barrel.

2. Apparatus for aging distilled alcoholic liquor in a storage barrel of the usual type provided with a conventional bung hole, said apparatus having, in combination, a curved heating element and a stirring element rotatable with respect to said heating element and capable of being simultaneously inserted into and withdrawn from said barrel with said heating element through said bung hole, supporting means for the stirrer element and heating element, said means being adapted to be secured in the bung hole to seal the same, a closed chamber mounted upon and forming a unit with said supporting member, said supporting means having a vent from the barrel into the chamber, a return drain from the chamber back to the barrel, a motor mounted upon the chamber, and driving connections between the motor and the stirrer member.

3. Apparatus for aging distilled alcoholic liquor in a storage barrel of the usual type provided with a conventional bung hole, said apparatus having, in combination, a curved heating element and a stirring element rotatable with respect to said heating element and capable of being simultaneously inserted into and withdrawn from said barrel with said heating element through said bung hole, supporting means for the stirrer element and heating element, said means being adapted to be secured in the bung hole to seal the same, said stirrer element being provided with an operating shaft journaled in said supporting means extending upwardly therefrom, a temperature indicating device mounted upon the supporting means, a pump operatively connected with said stirrer shaft, and a conduit system cooperating with the pump for effecting circulation of liquor within the barrel around the temperature indicating device and for returning the same to the barrel.

4. Apparatus for aging distilled alcoholic liquor in a storage barrel of the usual type provided with a conventional bung hole, said apparatus having, in combination, a curved heating element and a stirring element rotatable with respect to said heating element and capable of being simultaneously inserted into and withdrawn from said barrel with said heating element through said bung hole, supporting means for the stirrer element and heating element, said means being adapted to be secured in the bung hole to seal the same, said stirrer element having an operating shaft journaled in the supporting member, a motor for rotating the shaft, a pump operatively connected with the shaft, said stirrer member having a passage for effecting circulation of the liquor from within the barrel therethrough, and a temperature indicating device arranged to record the temperature of the liquor thus circulated.

5. Apparatus for aging distilled alcoholic liquor in a storage barrel of the usual type provided with a conventional bung hole having, in combination, a heating element, a hook-shaped stirrer element, both shaped to be capable of introduction into and withdrawal from the barrel through the usual bung hole therein, supporting means for the stirrer and heating elements, said means being adapted to be secured in the bung hole of the barrel, means for rotating the stirrer element with respect to said heating element, said stirrer element being provided with a deflecting portion whereby agitation is imparted to the liquor within the barrel both lengthwise of the barrel and transversely thereof.

6. Apparatus for aging distilled alcoholic liquor in a storage barrel of the usual type provided with a conventional bung hole having, in combination, a hook-shaped heating element, a hook-shaped stirrer element, a supporting member for both the stirrer and heating elements arranged to provide for disposing the stirrer element in substantially parallel relationship with the heating element for a portion of the length thereof, said heating element being shaped to be disposed in substantially close proximity to the sides of the barrel, means for effecting rotation of the stirrer element with respect to said heating element, said supporting member operating to seal the liquor within the barrel from the external atmosphere during the aging process.

7. Apparatus for aging distilled alcoholic liquor in a storage barrel of the usual type provided with a conventional bung hole, said apparatus having, in combination, a curved heating element and a stirring element rotatable with respect to said heating element and capable of being simultaneously inserted into and withdrawn from said barrel with said heating element through said bung hole, supporting means for said elements and for sealing said bung hole to prevent communication between the interior of said barrel and the atmosphere, and means for rotating said stirring means, said stirring element corresponding in shape to a portion of said heating element and lying adjacent thereto in at least one position of the stirring element.

8. In an apparatus for aging distilled alcoholic liquor in a storage barrel of the usual type provided with a conventional bung hole, the combination of a curved heating element capable of being inserted into and withdrawn from said barrel through said bung hole, a stirring element rotatable with respect to said heating element and substantially corresponding in shape to at least a portion of said heating element and lying adjacent said heating element in one position of the stirring element to provide for inserting and withdrawing said stirring element through said bung hole along with said heating element, means to support said heating and stirring elements and for sealing said bung hole during the aging process, and means for rotating said stirring means.
